UNITED STATES PATENT OFFICE.

ELLA REED, OF OKLAHOMA, OKLAHOMA.

ICE TONGS.

1,413,358.

Specification of Letters Patent. Patented Apr. 18, 1922.

Application filed April 22, 1921. Serial No. 463,495.

To all whom it may concern:

Be it known that I, ELLA REED, a citizen of the United States, residing at Oklahoma, in the county of Oklahoma and State of 5 Oklahoma; have invented a new and useful Ice Tongs, of which the following is a specification.

This invention relates to ice tongs.

This invention is to provide ice tongs 10 which are particularly adapted for family use where, in a great many instances, it is necessary for the purchaser to handle and carry the smaller cuts of ice some distance, and it is desirable to have a small, compact device for the purpose.

Another object is to provide a pair of tongs of this character, which is simple of construction, strong and durable and capable of self-adjustment to receive and carry 20 cuts of ice of varying dimensions and to offer a comfortable gripping portion to the hand of the operator so as to avoid tiring or injuring the same.

A further object is to provide a pair of 25 ice tongs which may be doubled or folded upon itself in such manner as to occupy only half of its normal space, so as to render the same capable of being carried in the pocket if desired, the device being manufactured of stock material and constructed 30 in such simple manner as to be readily manufactured and sold at a low cost.

A full and complete understanding of the 35 invention may be obtained from a consideration of the following detailed description, taken in connection with the accompanying drawing forming a part of this specification; it being understood that while the drawing shows a practical form of the invention, the latter is not confined to strict 40 conformity therewith; but may be changed or modified, so long as such changes or modifications mark no material departure from the salient features of the invention, as 45 specifically pointed out in the appended claims.

In the drawing, in which similar reference characters designate corresponding parts throughout the several figures:—

50 Figure 1 is a perspective view of the improved tongs in engagement with a maximum size piece of ice, the hand of the operator being indicated in dotted lines;

Figure 2 is a perspective view of the 55 tongs removed from the ice and shown in folded position.

In many communities it is the custom and the necessity for the consumer to carry ice for considerable distances, as for instance from docks, ware-houses or other central distributing points, or from ice wagons to residences, and the average householder does not purchase the larger size cuts of ice such as can be conveniently handled by the ordinary large size ice tongs generally used by the dealer, and the necessity for a cheap, handy device for domestic use has been a long-felt want.

As illustrated in the drawing, the device comprises a pair of similar tongs 1 and 2 respectively, each formed of steel rod material of a gage sufficiently strong to withstand the strain to which the tongs may be subjected. The tongs 1 and 2, which are hingedly joined together at their inner ends 70 to form a handle portion, are each provided at their free ends with inwardly directed, opposed hook portions 3—3 having their terminals pointed, as at 4—4 so as to facilitate their entrance into a cake of ice as is customary.

The hook portions 3—3 comprise terminals of downwardly and outwardly bowed portions 5—5 adapted to reach down and around the ends of the ice cake and extending from longitudinally disposed shanks 6—6 of substantially equal length and, as thus far described, the two tongs are identical in construction.

The rod comprising the tong 1 is returned 90 upon itself to form an end loop 7 and the terminal portion 8 thereof extended parallel to the shank 6 of said tong and in spaced relation to the same to provide a longitudinally disposed slot 9, the end 10 of the rod 95 being bent inwardly to close the slot at its outer end, and it will be observed that the portions 3, 6 and 8 of the tong 1 lie in a plane and that when in operative position the loop is in a vertical position.

On the other hand, the tong 2 is returned 105 upon itself in a horizontal plane, as at 11, and is passed through the slot 9 of the first named tong, the longitudinally disposed terminal portion of the rod comprising the last-named loop being normally located in a horizontal plane at one side of the shank of the tong 2 and the end thereof is inwardly bent toward the shank 6 to close the outer end of the slot thus formed.

The two members thus formed and hinged 110 together comprise a pair of tongs suitable

for handling cakes of ice of varying dimensions and sizes within the limits of the maximum opening of the same, and it will be seen that smaller cakes may be as readily 5 grasped by the tongs, the angular relation of the members becoming greater when a smaller cake of ice is being handled, as will be readily understood.

The loop portions of the members form 10 a convenient handle which may be grasped by the hand without injury or discomfort and the weight of the ice will tend to cause the aforesaid angular relation which may be resisted by the hand.

15 As indicated in Figure 2 of the drawing the two members may be folded to a position where one lies alongside of the other when the device may be readily placed in the pocket and carried or hung upon a nail when 20 not in use.

From the foregoing it will be seen that a simple, strong and durable ice tongs has been provided, which may be cheaply manufactured from stock material and sold at a 25 low cost, and that the same is capable of conveniently carrying different sized cakes of ice.

What is claimed is:

1. Ice tongs comprising a pair of hook-

shaped members hingedly connected together at one end for slidable engagement, each member being formed of a single piece of metal terminating in an inwardly-directed pointed prong, one of the members being provided, where hinged to the other, with a vertically-disposed elongated loop and the other member having a horizontally-disposed loop in traversing relation to the first-named loop to permit the members to be shortened or extended and to fold upon each other.

2. Ice tongs comprising a pair of hook-shaped members, each formed of a single piece of metal, one end of each member terminating in an inwardly directed pointed prong, the other end of the material forming each member, being returned upon itself and the end brought substantially in contact with the body of the member, thereby forming a pair of elongated loops which are interlocked and are in engagement with each other, said loops being arranged in different planes.

In testimony that I claim the foregoing as my own, I have hereto affixed my signature.

ELLA REED.
